UNITED STATES PATENT OFFICE.

ANDRÉ ALFRED LAPPIPE, OF PORT MENIER, ILE D'ANTICOSTI, QUÉBEC, CANADA.

GRAIN-SHOCKING DEVICE.

Application filed January 15, 1927. Serial No. 161,439.

The present invention pertains to a novel machine constructed to accompany a grain binder and to receive sheaves therefrom which are formed into the shocks and delivered to 5 the ground by the machine.

The novel machine comprises a receiver into which the sheaves are thrown from the binder. The receiver sets the sheaves upright on the floor of the machine, from which they 10 are delivered by suitable mechanism to the ground.

More specifically the machine comprises, in addition to the receiver, a floor provided with a longitudinally moving conveyor on 15 which is mounted a small transverse conveyor. The sheaf contained in the receiver is set upon the transversely moving conveyor and delivered to the longitudinally moving conveyor which is long enough to contain several sheaves. After the longitudinally moving conveyor has been filled, it is carried to the 20 rear end of the floor where the sheaves are deposited in a row. This operation is repeated until the entire floor of the machine 25 is covered with a shock of sheaves.

At this instant an automatic apparatus is set into motion to lower the floor, which is hinged, and to transfer the shock to the ground. This mechanism includes suitable 30 bars which bind the head of the shock so that the base thereof is spread by its engagement with the earth so that each sheaf assumes a conical position. The automatic mechanism further operates to raise the floor to its normal 35 position after the shock has been removed therefrom.

The invention is fully disclosed in the following description and in the accompanying drawings in which:

40 Figure 1 is a fragmentary plan elevation;

Figure 2 is a detail plan elevation at a lower level;

Figure 3 is a detail transverse section;

45 Figure 4 is a sectional view of one of the clutches;

Figure 5 is a side elevation of the machine;

Figure 6 is a detail vertical transverse section;

50 Figure 7 is a section on the line 7—7 of Figure 6;

Figure 8 is a detail vertical transverse section at the upper part of the machine;

Figure 9 is a detail section of the rear of the machine;

Figure 10 is a side elevation of the rear part 55 of the machine, showing the floor in lowered position;

Figure 11 is a detail side elevation at the forward part of the machine;

Figure 12 is a perspective view of the receiver;

Figure 13 is a detail vertical elevation;

Figure 14 is a detail section at right angles to Figure 13;

Figure 15 is a plan view of the machine; 65

Figure 16 is a detail elevation of one of the clutches at the rear of the machine;

Figure 17 is a detail elevation showing the manner in which the sheaves are delivered from the floor of the machine and set upon 70 the ground;

Figure 18 is a transverse vertical section;

Figure 19 is a detail vertical section;

Figure 20 is a section on the line 20—20 of 75 Figure 19;

Figure 21 is a detail side elevation;

Figure 22 is a section on the line 22—22 of 80 Figure 19;

Figure 23 is a detail transverse vertical section;

Figure 24 is a detail plan section; 85

Figure 25 is an enlarged section in a plane parallel to that of Figure 24;

Figure 26 is a detail vertical section;

Figure 27 is a section at right angles to 85 Figure 25;

Figure 28 is a detail transverse vertical section showing the worm mechanism at the forward part of the machine;

Figure 29 is a detail side elevation; 90

Figure 30 is a detail transverse vertical section;

Figure 31 is a section on the line 31—31 of Figure 30;

Figure 32 is a detail transverse vertical 95 section;

Figure 33 is a similar section showing a different adjustment of the parts;

Figure 34 is another detail transverse vertical section; 100

Figure 35 is a detail longitudinal vertical section, partly in elevation;

Figure 36 is a similar section showing a different adjustment of the parts;

5 Figure 37 is a detail section at right angles to Figure 36;

Figure 38 is a detail vertical elevation showing the floor actuating mechanism;

10 Figure 39 is a detail transverse vertical section; and

Figure 40 is a corresponding detail longitudinal section.

Reference to these views will now be made by use of like characters which are employed 15 to designate corresponding parts throughout.

The frame of the machine comprises a pair of longitudinal spaced rails 1 joined at an intermediate part by a sleeve 2 and provided at the rear ends with stub shafts 3. Through 20 the sleeve 2 is passed an axle 4 (Figure 28) formed intermediately with a worm 5 and carrying gears 6 at both ends. The stub shafts 3 carry the rear ground wheels 7 as clearly shown in Figures 1, 5 and 15, while 25 the frame is extended forwardly in the form of a tongue 8 (Figure 5) from which is suspended an arm 9 to carry the single forward ground wheel 10.

A rather short post 11 is mounted on the 30 forward part 8 for the support of a crown gear 12 having a pair of converged fingers 13 extending therefrom. Between this gear and the pinion 5 is suitably journaled a shaft 14 carrying at one end a pinion 15 meshing with the worm and at the other end another pinion 16 meshing with the gear 12. Between 35 the shaft 14 and the pinion 16 is interposed a clutch 17 operable by means of a link 18 which extends to a point within convenient reach of the operator or to a movable part 40 of the binder.

Between the sleeve 2 and the gear 12 is provided a rod 19 having at one end a universal joining connection 20 with the frame.

45 Between the members 2 and 19 is provided a curved track 21 engageable by a roller 22 carried by an intermediate portion of the shaft 19, the remaining end of the shaft carries a receiver 23 which is shown in greater 50 detail in Figure 12. The receiver has a flat bottom 24 and a curved wall 25, while three parallel slots 26 are cut in the bottom for a purpose presently to be described. The point of intersection of the fingers 13 is joined by 55 means of a link 27 to a collar 28 on the shaft 19. Adjacent the universal joint 20, a quadrant 29 is fixed to the frame for engagement by a pinion 30 on the shaft 19. It will be evident that if the clutch 17 is closed while the 60 machine is riding, rotary movement will be imparted to the gear 12 whereby the fingers 13 will swing the rod 19 and receiver 23 in an arcuate path along the track 21 first in one direction and then in the other.

In one of the rails 1, directly behind the 65 sleeve 2, is journaled a stub shaft 31 carrying a series of straight horizontal fingers 32 and a gate comprising curved fingers 33. When a sheaf of grain is thrown into the receiver and the latter swung in the manner 70 already described, the contents of the receiver are prevented from falling out by means of a curved guard 34 carried by the frame. When the receiver has reached its innermost limit it engages the fingers 33 and swings the 75 member 31 counterclockwise. The fingers 32 pass through the slots 26. Beneath the rail 1, the stub shaft 31 carries a pinion 35 with the interposition of a clutch 36 as shown in Figure 29. Directly forward of the pinion 80 35, a bracket 37 is secured to the rail 1 and supports one end of a spindle 38 (Figure 2) extending half way across the frame and provided at its ends with bevel pinions 39 and 40 respectively. The latter is in engagement 85 with the pinion 35.

Directly behind the spindle 38, another shaft 41 is journaled in the parallel rails 1. Bevel pinions 42 are mounted at the ends of the shaft 41 and are engaged by similar pinions 43 carried by clutch elements 44 supported by a transverse bar 45. The movable elements of the clutches are connected to bell crank levers 46 pivoted to the bar 45 and further joined by a link 47 having a finger 48 90 projecting from its centre. A spindle 49 is mounted medially of the frame and carries at one end a bevel pinion 50 meshing with the member 39. The shaft also carries a series of four fingers 51 adapted to engage the finger 48. It will be seen in Figure 2 that the extremities of the shaft 41 are provided with pinions 52 which mesh with the gears 6 already mentioned. The ends of the shaft 4 are geared to the stub shafts 3 by sprocket 100 chains 53 as clearly shown in Figure 1. Also, the clutches 44 are interconnected by a sprocket chain 54.

It will be evident that the gate 33 and consequently the stub shaft 31 are turned one-quarter revolution each time the gate is engaged by the receiver 23 in the manner already described. This movement is imparted through the pinion 35 to the pinion 40, spindle 38 and shaft 49. The four fingers 51 on the shaft 49 therefore engage the fingers 48 periodically and thus shift the link 47. In this manner one of the clutches is periodically 110 geared to the shaft 41 whereby the chain 54 is operated.

The ends of the shaft 41 are geared to stub shafts 55 (Figure 1) at the end of the frame by means of sprocket chains 56. Immediately rearward of the gate 33, a conveyor plate 57 is mounted transversely of the vehicle and adapted to move longitudinally thereof. To the lower surface of this plate 125 is secured a pair of brackets 58 (Figures 32, 33

and 34) through which is passed a rotatable shaft 59 having upturned ends 60. Between the laps of the chains 56 the shaft 59 carries a pair of double toothed members 61, and the upper lap of the chains is protected by cover plates 62 suitably supported by the frame of the machine.

Between the rails 1 a floor 63 is hinged-
ly mounted as indicated by the numeral
64 in Figure 10. The floor is provided near
its lateral edges with rails or tracks 64.
Arms 65 project from the rear edge of the
conveyor 57 and carry rollers 66 receivable
in the tracks 64. Another set of rollers 67
is carried by the conveyor 57 for guidance
in the tracks as illustrated in dotted lines in
Figure 1.

Upon the longitudinally moving conveyor
57 is mounted a transversely moving con-
veyor 68 having rollers 69 which ride in
grooves 70 cut in the member 57. To the bot-
tom of the conveyor 68 is hinged a lug 71
adapted to engage the chain 54 as shown in
Figures 30 and 31, whereby the chain moves
the conveyor transversely of the machine.

A series of gates 72, 73 and 74 are hinged-
ly mounted in a transverse wall 75 carried by
the conveyor 57. The end gate 72, farthest
removed from the gate 33, has a notch 76
(Figure 20) engageable by a dog 77 mount-
ed in the conveyor 57. When the dog is re-
ceived in the notch, the gate 72 is in the open
position shown in Figures 1 and 19.

In the conveyor 68 is mounted a pair of
rotatable studs 78 and 79 which are under
the tension of springs 80 as shown in Figures
13 and 14. These springs act in the direc-
tion of the arrows placed beside the studs
in Figure 14. The stud 78 carries a series
of curved gate bars 81 and a lug 82, while
the stud 79 carries straight fingers 83 and a
hook 84 adapted to receive the lug 82.

In the operation of the device as thus far
described let it be assumed that a sheaf of
grain is carried towards the gate 33 in the
manner already described. This gate is
swung by the action of the receiver 23 in
such a manner that the sheaf engages the
gate bars 81 and swings them outwardly.
The gate 32, also turning, moves the gate
83 through slots 26 against the sheaf. The
gate 83 is retained by the wall 75, and the
parts 82 and 84 are interlocked as shown in
Figure 14. As already stated the swinging
movement of the gate 33 causes operation of
the double clutches whereby the chain 54
moves and carries the conveyor 68 as far as
the gate 72. As the conveyor 68 approaches
the gate 72, a projection 85 (Figure 20)
passes over an abutment 86 on the dog 77
and releases the latter from the notch 76. The
gate is under tension by a spring 87 (Fig-
ures 19 and 22) and therefore binds the sheaf
against the wall 75. Since the conveyor 68
can no longer move in the same direction,

the clutch at this end is opened as a result
of the continuing rotation of the pinion 52
which is geared to the ground wheels 3. The
opening movement of the clutch is trans-
mitted through the bell crank levers 46 and
link 47, whereby the clutch at the starting
end is closed and the direction of the chain
57 reversed. The conveyor 68 now proceeds
in the reverse direction.

The link 47 and the bottom of the con-
veyor 68 are provided with friction blocks
88 and 89 respectively which are positioned
to engage one another when the conveyor is
in starting position, as illustrated in Figures
39 and 40. The engagement of these blocks
brings the clutches to open position and holds
them in that condition so that the conveyor
68 remains stationary until one of the clutches
is locked during the movement of the gate
33 as already described.

The conveyor 68 is provided with a mecha-
nism of the type shown in Figures 25, 26 and
27. This mechanism comprises a stud 90
which carries two fingers 91 and three shorter
fingers 92 spaced equidistantly around the
stud. The latter member also carries a ratch-
et 93 limited to movement in one direction by
a pawl 94 pivotally attached to the conveyor
68. To the conveyor 57 are attached teeth
95 adjacent the gates 73 and 74 as shown in
Figures 23 and 24, for the purpose of engag-
ing and turning the fingers 91 and 92. To
the bottom of each gate 73 and 74 is secured
a curved finger 96 which extends into a cor-
responding slot 97 cut through the conveyor
57 as shown in Figure 26. It will be obvious
that the shorter fingers 92 are not long enough
to reach the end of the finger 96.

This device is so adjusted that the short
finger 92 will pass the curved fingers 96
when the gates 73 and 74 are not to be op-
erated. After the first sheaf has been de-
posited at the gate 72 in the manner de-
scribed, one of the long fingers 92 will swing
the gate 73 across the conveyor 57. This
gate, being provided with a closing spring
similar to the member 87 in Figure 19, will
swing the second sheaf against the wall 75.
The conveyor 68 will now return through the
operation already described. It will be ap-
parent that when this conveyor commences its
return stroke after delivering a sheaf to one
of the gates, the said sheaf will be taken from
between the gates 81 and 83 whereby the
latter will assume their normal position un-
der the action of the springs 80.

The device described in connection with
Figures 25, 26 and 27, when adjacent the gate
74, is adjusted by its contacts with the fin-
ger 95, to swing this gate to receive the third
sheaf and bind it against the wall 75 as de-
scribed in connection with gate 73. After the
conveyor 68 has returned to starting position,
a fourth sheaf is deposited on the conveyor 68.

It will be seen in Figure 2 that the rear

end of the spindle 49 carries a finger 100 adapted to engage another finger 101 projecting from the shaft 59. The gearing controlling the shaft 49 is so arranged that after 5 four sheaves have been deposited and the stud 31 actuated four times, the finger 100 will engage the member 101 to tilt the shaft 59 on its axis. The double teeth 61 carried by this shaft will thus be brought into engagement 10 with the rearwardly moving lower lap of the chains 56, whereby the two conveyors 57 and 68 will be moved bodily to the rear ends of the rails 64.

It will be seen in Figure 5 that the rails 1 15 of the machine are provided with several posts arranged in pairs transversely of the machine as indicated by the numerals 102, 103, 104, 104', 153 and a fixed extension 129 enclosing the rotatable stud 31. When the 20 transverse conveyor 57 reaches its rearward limit, the upturned ends 60 of the shaft 59 engage a finger 105 on each post 102 as clearly shown in Figure 34. Due to this contact the shaft 59 is turned in its bearings whereby the 25 teeth 61 carried thereby are brought into the forwardly moving lap of the chains 56 so that the conveyor 57 is returned to its horizontal position. A plate 106 (Figure 3) having 30 a convex upper surface is secured to the frame at each end at the shaft 59 and is engaged by pins 107 carried by the double teeth 61 when the conveyor 57 reaches its forward limit. The curved plates 106 bring the teeth 61 into a neutral position to allow the conveyors 35 to be filled in the manner already described.

The posts 103, 104 and 104' are rounded at the base whereto rotatably supported gates 108, 109 and 110 are hinged as shown in Figure 15. The gates are comprised of two sets of arms at right angles to each other. When the finger 105 on the post 103 is engaged by the upturned ends 60, the gates 107 are swung so that the one branch thereof is brought parallel to the rail 1 while the other branch 45 engages the forward side of the sheaves and prevents them from creeping forwardly. Obviously the preceding gates 109 and 110 are also turned by the moving row of sheaves, 50 but are eventually caused to take the position described with reference to the gates 108.

A pair of curved bars 111 are hinged to the posts 102 to prevent the rearward row of sheaves from falling off the machine. The 55 construction and operation of these bars is described in greater detail below.

The remaining posts 104 and 104' carry star wheels consisting of fingers 112 as shown in Figures 6 and 7. Each such wheel carries 60 a ratchet 113 to prevent slipping. The shafts also carry a rotatable finger 114 adapted to lie in the path of the upturned ends 60. The longitudinally moving conveyor 57 carries an upwardly projecting dog 115 adapted 65 to engage the fingers 112 but not the member

114. Each rearward stroke of the conveyor 57 causes the star wheels to be swung to the extent of the space between two adjacent fingers thereof. The number of fingers associated with the devices 109 and 110 is such that 70 when a given row of sheaves is delivered to the floor, the corresponding fingers 114 will lie directly in the path of the upturned ends 60 so that the corresponding gates 114 will be 75 swung to engage the rear side of the row of sheaves and the teeth 61 will be thrown into the lower lap of the chains 56 for return movement.

With reference now to Figures 35, 36 and 38, it will be seen that racks 116 are slidably 80 mounted at the rear end of the frame. Each edge of the floor carries a pin 117 receivable and adapted to work in a groove 118 cut in the adjacent rack. Due to this support, the position of the floor depends on the position 85 of the racks.

Each side rail 1 contains a pin 119 adapted to enter a cavity 120 in the adjacent rack. The pin is normally pressed into the cavity by means of a spring 121 bearing on a collar 90 122 formed on the pin and on a screw cap 123 threaded into the side of the rail 1. The outer end of the pin is provided with a head 124.

As shown in Figure 21 the final or forward 95 post 104' carries still another finger 125 adapted to engage a bell crank lever 126 pivoted to the adjacent rail 1. The head 124 already described is engaged by another bell crank lever 127 pivoted adjacent thereto on 100 the frame of the machine. The bell crank lever 127 is joined to the member 126 by means of a link 128. When the post 104 has been turned to engage the last row of sheaves on the floor, the finger 125 swings the bell 105 crank lever 126 whereby the member 127 is also swung to remove the pin 119 from the cavity 120. The racks 116 are thus permitted to drop, carrying with them the floor 63 which falls to the position shown in Figure 110 10.

The intermediate part of the frame includes a pair of uprights 129 (Figure 5) between which is journaled a shaft 130 carrying a pair of sprocket wheels 131. The upper 115 ends 132 of the posts 102 serve to support a pair of slightly inclined bars 133. On these bars are mounted slidable bearings 134 rotatable with the bars and carrying pinions 135 which mesh with perpendicular pinions 136. 120 The latter are mounted on slidable bearings 136' (Figure 16) from which extend stub shafts 136'' carrying a pair of sprocket wheels 137 in line with the members 131.

The lower end of each rod 133 carries a 125 bevel pinion 138 meshing with another pinion 139 carried by the stub shaft 55 which is driven by the chain 56 as shown in Figure 1. The shafts 133 are therefore constantly in motion during the travel of the machine, 130

but a clutch 140 (Figure 16) is provided adjacent each gear 136.

The shafts 130 and 136 support a trough 141 on which is built a superstructure 142 comprising tracks 143 which contain the chains connecting the sprockets 131 and 137. In the trough is received a pair of blocks 144 which are joined by a cross shaft 145 (Figure 17) passed therethrough. The shaft is further joined to the sprocket chains by links 146 as shown in Figure 5.

It will be seen in Figure 16 that each of the clutches 140 comprises a clutch face 147 carried by the pinion 136, a slideable face 148, having a cam face and adjacent this a bar 149 having cam edges 150 receivable between the member 148 and another cam face 151 carried by the sprocket wheel 137. The spring 152 is placed between the gear 136 and the arm 149 to normally hold the clutch open.

To one of the fixed posts 153 of the frame (Figures 5 and 10) is pivotally connected one end of an arm 154, the other end of which is connected by means of a link 155 to a bar 156 loosely mounted on the rear axle. The free end of this bar is adapted to work in a slot 157 cut in the edge of the floor 63, so that the link 155 is actually connected to the floor. A rod 158 extends outwardly from the free end of the bar 154 and is joined to the cross shaft 145. This construction is provided at each side of the machine. When the floor drops by the operation already described, the rods 158 and the cross shaft 145 are also lowered.

To each of the blocks 144 is pivoted a bell crank lever 159 having one end engageable by a pin 160 on the block 144. Each bell crank lever is connected by means of a link 161 to the corresponding arm 149 already described in connection with Figure 16. It will be apparent that these linkages control the clutches 140. Spring pressed means may be provided for normally holding the bell crank levers 159 in such a position that the clutches are held open. When the rods 158 drop, the bell crank levers 159 are turned and the links 161 are pulled to bring the clutches into the closed position which is illustrated in Figure 16.

The trough 141 and the lower lap of the track 143 are formed with alined bearings 162 and 163 respectively, as shown in Figure 8, wherein is journaled a shaft 164 at each side of the machine. These shafts carry the curved arms 111 which have been previously mentioned. Each such arm has a boss 165 surrounding its shaft. Each shaft has a stud 166 passing through a slot 167 cut in the boss and secured to a spring 169 partly surrounding the boss and engaging the arm whereby the latter is normally held in the position shown in Figure 15. The upper part of each arm carries a pin 170 engageable by a similar

member 171 carried by the block 144 as also shown in Figure 8. As the chain within the track 143 is moved through the mechanism already described the pins 171 on the block 144 cause the shafts 164 to be turned whereby the arms 111 are carried to open position. At the same time the sheaves are engaged by the cross shaft 145 as shown in Figure 17 and thereby carried off the floor upon the ground. The heads of the sheaves are compressed as shown in Figure 17, and the frictional engagement of the lower ends of the sheaves with the earth in passing off the floor causes the sheaves to be spread at the bottom, as a result of which they remain standing on the ground as previously described in detail.

To the inner side of each of the rails 1 is secured a track 172 (Figures 35 to 38) on which slides a block 173. The rear end of the block is formed with the slot 174 having an enlargement 175. A square shaft 176 has a reduced end 177 receivable and movable in the slot and enlargement thereof. The rear edge of each of the racks 116 has a T-shaped rib 178 slidably received in the adjacent block 173 whereby the rack is movable with the block and at the same time slidably mounted in relation thereto in the vertical direction. Near the toothed edge of each rack is mounted a pinion 179 which is either carried by the rear axle of the machine as shown in Figure 1 or suitably driven thereby. Each block 173 is further formed with a cavity 180 into which extends a fin 181 projecting from the track 172. In this cavity is mounted a coil spring 182 between the fin and the forward wall of the cavity, whereby the rack 116 is normally pushed towards the pinion 179. The reduced end 177 of the square shaft 176, however, normally lies in the enlargement 175 and perpendicular slot 174 whereby shifting movement of the block 173 is obstructed.

The upper part of each square shaft 176 carries a right angular finger 183 which lies in the path of lugs 184 on the chain within the track 143 as illustrated in Figure 5. After the sheaves have been discharged from the floor of the machine, the lugs 184 engage the fingers 183 and turn the square shafts 176 so that the reduced ends thereof are in line with the slots 174. The blocks 173 are now free to move under the action of the springs 182, whereby the racks 116 are brought into engagement with the pinion 179 as shown in Figure 36. The movement of the vehicle turns the pinions and causes the racks and the floor to be raised to normal position.

In Figure 5 is shown an extension 185 provided at the rear end of the trough 141. It is to be noted that this trough comprises a single lap, so that the block 144 rides therein backwardly and forwardly during a complete cycle of the chain. Therefore, when the chain turns in clockwise direction, the block 144

precedes the lugs 184. At the end of the rearward stroke the block 144 enters the extension 185 while the link 146 is accommodated to the movement of the chain due to the pivotal connection between these parts.

As shown in Figure 38, the frame has a bell crank lever 186 pivoted thereto while the rack carries a cam 187. In the rising movement of the rack the two cams engage one another 10 as in Figure 38, and the rack and block 173 are therefore moved rearwardly due to the spacing between the rack and pinion caused by the engagement of the cams. The lugs 184 return past the finger 183 at the instant 15 that the reduced shaft end 177 is again received in the enlargement 175. The engagement between the lugs 184 and finger 183 turns the shaft 90° to the position shown in Figure 35 whereby the block 173 is again 20 locked in its rearward position. On return of the block to the position shown in Figure 5, the rearward clutches 140 are again opened.

The bars 111 are in open position only during the movement of the pin 170 by 25 the pin 171. After these pins have become disengaged the bars return to the sheaf so that the head of the shock on the floor 63 is constantly held between the bars and the cross shaft 145 to permit the formation of 30 a conical bundle standing on the ground as already described. Naturally, the bars 111 give way under the pressure of the cross shaft 145 in order to permit transfer of the sheaves to the ground. The pawl and ratchet mechanism illustrated in Figure 4 is applied to the 35 rear stub shafts 3. The ratchet 188 is associated with the adjacent pinion 179 and sprocket chain 53 through the shaft 3. The pawl 189 is carried by an outer shaft 3' which turns with the ground wheels. When the vehicle is moving forward, the pawl turns the ratchet and operates the mechanism described. If the machine is backed up the pawl merely slips over the ratchet so that the 40 parts associated with the latter remain operative.

While a specific embodiment of the invention has been illustrated and described, it is to be understood that various alterations in 45 the details of construction may be made without departing from the spirit of the invention as indicated by the appended claims.

Having thus fully described the invention, what I claim as new and desire to protect by 50 Letters Patent is:

1. A machine of the character described comprising a wheeled frame, a hinged floor supported therein, a conveyor movable longitudinally of the floor, a receiver supported by said frame and adapted to swing and tilt, a transverse conveyor movable on the first named conveyor and adapted to receive from 55 said receiver and deposit sheaves on said longitudinally moving conveyor, means for re-

moving conveyor to said floor, and means for removing said sheaves from said floor to the ground.

2. A machine of the character described comprising a wheeled frame, a hinged floor 70 supported therein, a conveyor movable longitudinally of the floor, a receiver supported by said frame and adapted to swing and tilt, a transverse conveyor movable on the first named conveyor and adapted to receive from 75 said receiver and deposit sheaves on said longitudinally moving conveyor, gates on said longitudinally moving conveyor and adapted to take the sheaves from said transversely moving conveyor, gates on said floor and adapted to take the sheaves from said longitudinally moving conveyor, and means for removing said sheaves from the floor to the ground.

3. A machine of the character described 85 comprising a wheeled frame, upright racks 90 slidably mounted in said frame, a hinged floor mounted in said frame, means for depositing sheaves on said floor, an upper frame supported by said first named frame and racks, an endless chain movable in said upper frame and geared to the ground wheels of the machine, and a cross bar movable with said chain and adapted to remove sheaves from 95 said floor to the ground.

4. A machine of the character described comprising a wheeled frame, a hinged floor supported therein, a conveyor movable longitudinally of the floor, a receiver supported by said frame and adapted to swing and tilt, 100 a transverse conveyor movable on the first named conveyor and adapted to receive from said receiver and deposit sheaves on said longitudinally moving conveyor, means for removing sheaves from said longitudinally moving conveyor to said floor, an upper frame hingedly attached to said first named frame, 105 an endless chain movable in said upper frame and geared to the ground wheels of the machine, and a cross bar movable with said chain and adapted to remove sheaves from 110 said floor to the ground.

5. A machine of the character described comprising a wheeled frame, a hinged floor supported therein, a conveyor movable longitudinally of the floor, a receiver supported by said frame and adapted to swing and tilt, a transverse conveyor movable on the first named conveyor and adapted to receive from 115 said receiver and deposit sheaves on said longitudinally moving conveyor, gates on said longitudinally moving conveyor and adapted to take the sheaves from said transversely moving conveyor, gates on said floor and adapted to take the sheaves from said longitudinally moving conveyor, an upper frame hingedly attached to said first named frame, 120 an endless chain movable in said upper frame and geared to the ground wheels of the machine, and a cross bar movable with said chain 125 130

and adapted to remove sheaves from said floor to the ground.

6. A machine of the character described comprising a wheeled frame, upright racks 5 slidably mounted in said frame, a hinged floor mounted in said frame, means for depositing sheaves on said floor, an upper frame supported by said first named frame and racks, an endless chain movable in said upper frame 10 and geared to the ground wheels of the machine, a cross bar movable with said chain and adapted to remove sheaves from said floor to the ground, clutches controlling said endless chain, and means carried by said chain 15 for operating said clutches.

7. A machine of the character described comprising a wheeled frame, a hinged floor supported therein, a conveyor movable longitudinally of the floor, a receiver supported by 20 said frame and adapted to swing and tilt, a transverse conveyor movable on the first named conveyor and adapted to receive from said receiver and deposit sheaves on said longitudinally moving conveyor, means for removing 25 sheaves from said longitudinally moving conveyor to said floor, an upper frame hingedly attached to said first named frame, an endless chain movable in said upper frame and geared to the ground wheels of the machine, a cross bar movable with said chain and adapted to remove sheaves from said floor to the ground, clutches controlling said endless chain, and means carried by said chain for 30 operating said clutches.

8. A machine of the character described comprising a wheeled frame, a hinged floor supported therein, a conveyor movable longitudinally of the floor, a receiver supported by 35 said frame and adapted to swing and tilt, a transverse conveyor movable on the first named conveyor and adapted to receive from said receiver and deposit sheaves on said longitudinally moving conveyor, gates on said longitudinally moving conveyor and adapted 40 to take the sheaves from said transversely moving conveyor, gates on said floor and adapted to take the sheaves from said longitudinally moving conveyor, an upper frame hingedly attached to said first named frame, 45 an endless chain movable in said upper frame and geared to the ground wheels of the machine, a cross bar movable with said chain and adapted to remove sheaves from said floor to the ground, clutches controlling said endless chain, and means carried by said chain for 50 operating said clutches.

9. A machine of the character described comprising a wheeled frame, a hinged floor supported therein, a conveyor movable longitudinally of the floor, a receiver supported by 55 said frame and adapted to swing and tilt, a transverse conveyor movable on the first named conveyor and adapted to receive from said receiver and deposit sheaves on said longitudinally moving conveyor, gates on said 60

longitudinally moving conveyor and adapted to take the sheaves from said transversely moving conveyor, gates on said floor and adapted to take the sheaves from said longitudinally moving conveyor, an upper frame 70 hingedly attached to said first named frame, an endless chain movable in said upper frame and geared to the ground wheels of the machine, a cross bar movable with said chain and adapted to remove sheaves from said floor to the ground, clutches controlling said endless chain, means carried by said chain for operating said clutches, pinions adapted to raise said racks and floor, said pinions being operatively connected to the ground wheels. 80

10. A machine of the character described comprising a wheeled frame, upright racks slidably mounted in said frame, a hinged floor mounted in said frame, means for depositing sheaves on said floor, an upper frame 85 supported by said first named frame and racks, an endless chain movable in said upper frame and geared to the ground wheels of the machine, a cross bar movable with said chain and adapted to remove sheaves from said floor to the ground, pinions adapted to raise said racks and floor, said pinions being operatively connected to the ground wheels and normally spaced from said racks, spring pressed blocks adapted to retain said racks 90 at a distance from said pinions and means for releasing said blocks. 95

11. A machine of the character described comprising a wheeled frame, a hinged floor supported therein, a conveyor movable longitudinally of the floor, a receiver supported by 100 said frame and adapted to swing and tilt, a transverse conveyor movable on the first named conveyor and adapted to receive from said receiver and deposit sheaves on said longitudinally moving conveyor, means for removing sheaves from said longitudinally moving conveyor to said floor, an upper frame hingedly attached to said first named frame, an endless chain movable in said upper 105 frame and geared to the ground wheels of the machine, a cross bar movable with said chain and adapted to remove sheaves from said floor to the ground, pinions adapted to raise said racks and floor, said pinions being operatively connected to the ground wheels and normally spaced from said racks, spring pressed blocks adapted to retain said racks 110 at a distance from said pinions, and means for releasing said blocks. 115

12. A machine of the character described comprising a wheeled frame, a hinged floor supported therein, a conveyor movable longitudinally of the floor, a receiver supported by 120 said frame and adapted to swing and tilt, a transverse conveyor movable on the first named conveyor and adapted to receive from said receiver and deposit sheaves on said longitudinally moving conveyor, gates on said 125

longitudinally moving conveyor and adapted to take the sheaves from said transversely moving conveyor, gates on said floor and adapted to take the sheaves from said longitudinally moving conveyor, an upper frame hingedly attached to said first named frame, an endless chain movable in said upper frame and geared to the ground wheels of the machine, a cross bar movable with said chain and adapted to remove sheaves from said floor to the ground, pinions adapted to raise said racks and floor, said pinions being operatively connected to the ground wheels and normally spaced from said racks, spring 15 pressed blocks adapted to retain said racks at a distance from said pinions, and means carried by said chain for releasing said blocks.

13. A machine of the character described comprising a wheeled frame, upright racks 20 slidably mounted in said frame, a hinged floor mounted in said frame, means for depositing sheaves on said floor, an upper frame supported by said first named frame and racks, an endless chain movable in said upper frame and geared to the ground wheels of the machine, a cross bar movable with said chain and adapted to remove sheaves from said floor to the ground, clutches controlling 25 said endless chain, means carried by said chain for operating said clutches, pinions adapted to raise said racks and floor, said pinions being operatively connected to the ground wheels and normally spaced from 30 said racks, spring pressed blocks adapted to retain said racks at a distance from said pinions, and means carried by said chain for releasing said blocks.

14. A machine of the character described comprising a wheeled frame, upright racks 40 slidably mounted in said frame, a hinged floor mounted in said frame, means for depositing sheaves on said floor, an upper frame supported by said first named frame and racks, an endless chain movable in said upper frame and geared to the ground wheels of the machine, a cross bar movable with said chain and adapted to remove sheaves from said floor to the ground, clutches for controlling 45 said endless chain, means carried by said chain for operating said clutches, pinions adapted to raise said racks and floor, said pinions being operatively connected to the ground wheels and normally spaced from said racks, spring pressed blocks adapted to retain 50 said racks at a distance from said pinions, and means carried by said chain for releasing said blocks.

15. A machine of the character described comprising a wheeled frame, a hinged floor 60 supported therein, a conveyor movable longitudinally of the floor, a receiver supported by said frame and adapted to swing and tilt, a transverse conveyor movable on the first named conveyor and adapted to receive from 65

said receiver and deposit sheaves on said longitudinally moving conveyor, gates on said longitudinally moving conveyor and adapted to take the sheaves from said transversely moving conveyor, gates on said floor and adapted to take the sheaves from said longitudinally moving conveyor, an upper frame hingedly attached to said first named frame, an endless chain movable in said upper frame and geared to the ground wheels 70 of the machine, a cross bar movable with said chain and adapted to remove sheaves from said floor to the ground, clutches for controlling said endless chain, means carried by said chain for operating said clutches, pinions adapted to raise said racks and floor, 75 said pinions being operatively connected to the ground wheels and normally spaced from said racks, spring pressed blocks adapted to retain said racks at a distance from said pinions, and means carried by said chain for releasing said blocks.

16. A machine of the character described comprising a wheeled frame, upright racks 80 slidably mounted in said frame, a hinged floor mounted in said frame, means for depositing sheaves on said floor, an upper frame supported by said first named frame and racks, an endless chain movable in said upper frame and geared to the ground wheels 85 of the machine, a cross bar movable with said chain and adapted to remove sheaves from said floor to the ground, clutches controlling said endless chain, means carried by said chain for operating said clutches, pinions adapted to raise said racks and floor, 90 said pinions being operatively connected to the ground wheels and normally spaced from said racks, spring pressed blocks adapted to retain said racks at a distance from said pinions, and means carried by said chain for releasing said blocks.

17. A machine of the character described comprising a wheeled frame, upright racks 95 slidably mounted in said frame, a hinged floor mounted in said frame, a locking device for retaining said racks in raised position, means for depositing sheaves on said floor, an upper frame supported by said first named frame and racks, an endless chain mounted in said upper frame and gears to the ground wheels, a cross bar movable with said endless chain and adapted to remove sheaves from said floor to the ground, and automatic means for 100 releasing said retaining device for the rack.

18. A machine of the character described comprising a wheeled frame, upright racks 105 slidably mounted in said frame, a hinged floor mounted in said frame, a locking device for retaining said racks in raised position, means for depositing sheaves on said floor, 110 an upper frame supported by said first named frame and racks, an endless chain mounted in said upper frame and gears to the ground wheels, a cross bar movable with said endless 115

- chain and adapted to remove sheaves from said floor to the ground, automatic means for releasing said retaining device for the rack, pinions adapted to raise said racks and floor, 5 said pinions being operatively connected to the ground wheels and normally spaced from said racks, spring pressed blocks adapted to retain said racks at a distance from said pinions and means for releasing said blocks.
10. 19. A machine of the character described comprising a wheeled frame, a hinged floor supported therein, a conveyor movable longitudinally of the floor, a receiver supported by said frame and adapted to swing and tilt, 15 a transverse conveyor movable on the first named conveyor and adapted to receive from said receiver and deposit sheaves on said longitudinally moving conveyor, gates on said longitudinally moving conveyor and 20 adapted to take the sheaves from said transversely moving conveyor, gates on said floor and adapted to take the sheaves from said longitudinally moving conveyor, an upper frame hingedly attached to said first named
- frame, an endless chain movable in said upper frame and geared to the ground wheels of the machine, a cross bar movable with said chain and adapted to remove sheaves from said floor to the ground, clutches controlling said endless chain, means carried by 25 said chain for operating said clutches, a locking device for retaining said racks in raised position, means for depositing sheaves on said floor, an upper frame supported by said first named frame and racks, an endless chain mounted in said upper frame and gears to the ground wheels, a cross bar movable with said endless chain and adapted to remove sheaves from said floor to the ground, 30 automatic means for releasing said retaining device for the rack, pinions adapted to raise said racks and floor, said pinions being operatively connected to the ground wheels and normally spaced from said racks, spring 35 pressed blocks adapted to retain said racks at a distance from said pinions and means for releasing said blocks.

ANDRÉ ALFRED LAPLÉ.
